UNITED STATES PATENT OFFICE

LAURI TOIVONEN, OF EAST ELMHURST, NEW YORK

WINDOW-SHADE ADJUSTER

Application filed December 27, 1927. Serial No. 242,723.

This invention relates to a new and useful device in the nature of an adjustable shade fixture especially adapted to support a window shade roller and to permit the shade to 5 be adjusted vertically.

The object of the invention is to provide an adjustable shade fixture of simple and efficient construction which may be manufactured and marketed at a low price.

10 A further object of the invention is to provide a device of the class described of novel construction and arrangement of parts hereinafter more fully described, claimed and illustrated in the accompanying drawing.

15 Fig. 1 is a front view of a window embodying my improved device.

Fig. 2 is an enlarged front elevational view of my improved device.

Fig. 3 is a front elevational view of the 20 locking mechanism and operating lever as embodied therein.

Fig. 4 is a similar view to Fig. 2 showing the corresponding pair of the device.

Fig. 5 is a transverse sectional view taken 25 on the line 5—5 of Fig. 3.

Fig. 6 is a similar view to Fig. 5 showing another means of holding the spring.

Fig. 7 is a similar sectional view taken on the line 7—7 of Fig. 2.

30 Fig. 8 is a side elevational view of the operating lever, per se, of the device.

As here embodied my improved device comprises a pair of brackets 10, or supports, formed from a sheet metal plate. The vertical edges of the brackets 10 are formed or bent curved as at 11 and 12 so as to provide a guide, and are provided with upper and lower flanged elements 13 and 14.

The shade roller engaging member 15 is 40 slidably mounted in the extended portion 16 of the slide 17, and is provided with a flanged element 18, as a means of holding the said engaging member in position in the slide 17.

The expansion spring 19 is adapted to engage 45 in the engaging member 15, and is positioned in the slide 17, which is provided with a depressed portion 20, as a means of holding the spring 19 in position. The latter described construction is such as will permit 50 the engaging member 15 to be urged outward-

ly as a means of retaining the tip 21 of the shade roller 22. Another method of holding spring 19 in position is shown in Fig. 6, in which the spring is held in position by an annular depressed portion 20' which engages 55 the outside of the spring. The engaging member 15 has formed therein a suitable opening 23, of a desired contour as may be required to receive the said tip 21 of the shade roller. The extended portion 16 of the slide 17 is provided with a raised element 16', adjacent to the periphery of the aperture formed in the said portion 16.

The slide 17 is slidably mounted vertically in the bracket 10, and is provided with upper 60 and lower curved portions 24 and 25, adapted to receive the operating lever 26, which extends vertically downwardly therefrom through an aperture formed in the lower flanged element 14 of the bracket 10. The operating lever 26 is provided with a handle element 27, formed or bent approximately at right angle to the main portion of the operating lever 26. The operating lever 26 is provided with an offset or eccentric portion 70 28, positioned intermediate the above mentioned upper and lower curved portions 24 and 25 of the slide 17.

The brackets 10 have formed therein apertures 32 adapted to receive wood screws or 80 the like, as a means of securing the brackets to the inner portion 33 and 34 of the window pane 35, in proximity to the upper portion thereof.

The above described construction is such 85 as will permit the slide 17 to be adjusted vertically by means of the said operating lever, and which will permit the eccentric portion 28 of the operating lever 27 to frictionally engage the side 12 of the bracket 10, when the handle element 27 of the said operating lever 26 is in approximate alignment with the inner surfaces of the said window frame, so as to securely hold the said slide in position. 90

It is obvious from the foregoing construction that the shade 22 may be adjusted vertically, so as to permit of a free passage of air from the window open at the top. 95

Having thus described my invention what 100

I claim as new and desire to secure by United States Letters Patent is:

1. A window shade adjuster, comprising a member for attachment upon one of the side-forming members of a window frame and having guide elements for guiding a slide longitudinally along said side-forming member, a slide member mounted on said guide elements and adapted for supporting a window shade, and a lever rotatively mounted on said slide longitudinally of the path of motion of said slide and extending along said side-forming member out of the vicinity of a shade supported on said slide member and formed with an offset portion engageable against said guide elements for frictionally holding the slide in adjusted positions.
  2. A window shade adjuster, comprising a member for attachment upon one of the side-forming members of a window frame and having guide elements for guiding a slide longitudinally along said side-forming member, a slide member mounted on said guide elements and adapted for supporting a window shade, and a lever rotatively mounted on said slide longitudinally of the path of motion of said slide and extending along said side-forming member out of the vicinity of a shade supported on said slide member, and coacting means on said lever and said member for frictionally holding the slide in adjusted positions on said member upon slight rotation of said lever.
- 35 In testimony whereof I have affixed my signature.

LAURI TOIVONEN.
